(57) **CLAIM**

The ornamental design for the multifunctional cap as shown and described.

DESCRIPTION

4. Multifunctional cap

The figures show the design of a multifunctional cap, which are detachable and capable of plugging into and interconnecting with one another, similar to a modular toy building block construction system.

Figure 4.1 is a first perspective view of the multifunctional cap;

Figure 4.2 is a top plan view thereof;

Figure 4.3 is a first side view thereof;

Figure 4.4 is a second side view thereof;

Figure 4.5 is a second perspective view thereof;

Figure 4.6 is a third perspective view thereof, shown in an environment of use; and

Figure 4.7 is a fourth perspective view thereof, shown in another environment of use.

The broken lines showing a bag-type container in Fig. 4.6 and additional multifunctional caps in Fig. 4.7 represent environmental structure, and form no part of the claimed design.
